FIG. 1 is a perspective view from the left front side of a combined door handle and lock housing embodying my invention, shown mounted on a door which is shown in phantom;

FIG. 2 is an enlarged foreshortened right side elevation taken as indicated by the lines and arrows 2—2 in FIG. 1;

FIG. 3 is an enlarged foreshortened rear elevation of the embodiment shown in FIG. 1;

FIG. 4 is a greatly enlarged top view taken as indicated by the lines and arrows 4—4 in FIG. 3;

FIG. 5 is a greatly enlarged section taken as indicated by the lines and arrows 5—5 in FIG. 3;

FIG. 6 is a perspective view taken from the left front side of another combined door handle and lock housing embodying my invention, shown mounted on a door which is shown in phantom;

FIG. 7 is an enlarged foreshortened right side elevation taken as indicated by the lines and arrows 7—7 in FIG. 6;

FIG. 8 is an enlarged foreshortened rear view of the embodiment shown in FIG. 6;

FIG. 9 is a greatly enlarged top view taken as indicated by the lines and arrows 10—10 in FIG. 8;

FIG. 10 is a greatly enlarged section taken as indicated by the lines and arrows 10—10 in FIG. 8;

FIG. 11 is a perspective view taken from the left front side of another combined door handle and lock housing embodying my invention, shown mounted on a door which is shown in phantom;

FIG. 12 is an enlarged foreshortened right side elevation taken as indicated by the lines and arrows 12—12 in FIG. 11;

FIG. 13 is an enlarged foreshortened rear view taken as indicated by the lines and arrows 13—13 in FIG. 12;

FIG. 14 is a greatly enlarged top view taken as indicated by the lines and arrows 14—14 in FIG. 13;

FIG. 15 is a greatly enlarged section taken as indicated by the lines and arrows 15—15 in FIG. 13;

FIG. 16 is a perspective view taken from the left front side of another combined door handle and lock housing embodying my invention, shown mounted on a door which is shown in phantom;

FIG. 17 is an enlarged foreshortened right side elevation taken as indicated by the lines and arrows 17—17 in FIG. 16;

FIG. 18 is an enlarged foreshortened rear view taken as indicated by the lines and arrows 18—18 in FIG. 17;

FIG. 19 is a greatly enlarged top view taken as indicated by the lines and arrows 19—19 in FIG. 18; and

FIG. 20 is a greatly enlarged section taken as indicated by the lines and arrows 20—20 in FIG. 18.

The shading employed does not connote actual appearance, but is an expedient to best illustrate shape.

The door shown in phantom lines forms no part of the design and has been included for purposes of illustrating the environment only.

Portions have been foreshortened on the drawings for convenience of illustration.

The front view of each embodiment is identical to the rear view of that embodiment.

CROSS-REFERENCE TO RELATED APPLICATIONS

This application incorporates by reference my prior copending applications Ser. No. 20,195, filed Nov. 20, 1969, Ser. No. 21,811, filed Mar. 9, 1970, Ser. No. 10,892, filed Mar. 8, 1968, and Ser. No. 13,607, filed July 18, 1968, all now abandoned and discloses and claims, in part, subject matter disclosed and claimed therein.

I claim:

The ornamental design for a combined door handle and lock housing, as shown and described.
